(57) **CLAIM**

The ornamental design for a container holder with a camera, as shown and described.

DESCRIPTION

FIG. 1 is a front, top perspective view of a container holder with camera;

FIG. 2 is a rear, bottom perspective view thereof;

FIG. 3 is a side view thereof;

FIG. 4 is an opposite side view thereof;

FIG. 5 is a front view thereof;

FIG. 6 is a rear view thereof;

FIG. 7 is a top plan view thereof; and,

FIG. 8 is a bottom plan view thereof.

The broken lines illustrate portions of the container holder with camera that form no part of the claimed design.
